Attorney

This original short-handwritten formal statement is made to be read and to be given the same effect as any other formal statement of the same character, and is made to be read and to be given the same effect as any other formal statement of the same character.

UNITED STATES PATENT OFFICE

Serial No. 73,000, filed January 2, 1936, 2,180,201

PITCH BAND REED

Walde Henry Fish, Central Falls, R. I., assignor to American Supply Company, Central Falls, R. I., a corporation of Rhode Island

Application November 19, 1936, Serial No. 111,635

2 Claims. (Cl. 139—192)

My invention relates to improvements in pitch band reeds.

Pitch band reeds are the oldest type of loom reeds. They originated in old-fashioned hand looms where each dent was actually a reed and pitch impregnated cord was employed to hold the reeds together at spaced distances. Eventually metal strips displaced the use of reeds as dents as shown in Patent No. 315,590 to E.

10 Adamson in 1885. The substitution of metal strips for reeds as dents is substantially the only important improvement that has taken place in pitch band reeds for centuries up to my present invention. These pitch band reeds have been 15 usually used in the weaving of cotton or woolen fabrics and have been relatively cheap as distinguished from the so-called all-metal reeds, in which there has been a considerable development, but which are much more expensive and are 20 used for the weaving of silk and rayon and fine cotton fabrics.

A great difficulty with the standard type of pitch band reed has been that the edges of the dents have rested against the inner wooden surfaces of the semi-cylindrical wooden ribs, two of 25 which with pitch impregnated cord have made up each pitch band, and on the vibration which occurs in use, these edges have had a tendency to become imbedded in the non-homogeneous wood.

30 Pitch impregnated yarn or cord has been generally employed in this country in the manufacture of pitch band reeds for the reason that as the dents are compressed in the manufacture of the reed, the pitch tends to form a homogeneous tubular resilient covering over the entire outer 35

surface of the cord and ribs which is somewhat elastic throughout the length of the pitch band to permit the ready axial expansion thereof, as a knot might pass between two dents in one portion thereof, and ready resilient contraction 40

thereof throughout its length after passage of said knot to again provide the original spacing of said dents. If, however, the dent ends become imbedded into the wood, this ready resilient axial 45

expansibility and contractability of the pitch band shell is considerably lessened if not prevented. The imbedding of said dent edges in the wood has had the following disadvantageous results, 50 namely, (1) that as the wood construction is always full of knots or other irregularities, the alignment and the spaces between the individual dents have tended to become varied due to the fact that one dent finds a softer spot in the wood than another or may have to move around a knot 55 to find such a soft spot, (2) the edges of the dents

have become so imbedded in the wood as to impair the axial expansibility and contractability of the pitch band reed in use, and (3) as they have become imbedded into the wood they have flattened the tubular pitch impregnated cord into 5 ellipsoidal shape, thereby tending to loosen the pitch impregnated cord and break up the tubular rigid shell formed throughout the length of the reed.

To prevent the edges of the dents from becoming imbedded in the wood I therefore provide means, in my preferred embodiment comprising flat protective strips of hard material of substantially the width of said pitch bands or the flat inner surfaces of said wooden ribs, interposed between said flat inner surfaces of said ribs and the dent edges. It is apparent that this means also provides bearing means to insure a somewhat evenly distributed axial expansibility and contractability of the dents throughout the 20 length of the pitch band.

Employing my invention, it is apparent that the reeds are not only strengthened, but that they function better in use, and that the life of each reed is very greatly prolonged. Inasmuch as opposite edges of the dents are clamped between longitudinally extending hard surfaces, they maintain an even alignment of the dents and insure against any one individual forwardly projecting dent striking the shuttle and tending 30 to wear it out.

These and such other objects of my invention as may hereinafter appear will be best understood from a description of the accompanying drawing which illustrates an embodiment thereof.

In the drawing, Fig. 1 is a front elevation of an improved reed constructed in accordance with my invention with portions of the upper pitch band thereof successively broken away to show the construction thereof.

Fig. 2 is a vertical sectional view thereof taken along the line 2—2 of Fig. 1.

In the drawing, wherein like characters of reference generally indicate like parts throughout, 45 generally indicates an improved pitch band 45 reed constructed in accordance with my invention. Said pitch band reed comprises the dents 12 substantially equidistantly spaced as usual and the longitudinally extending pitch bands 14 flexibly joining opposite ends of the dents together 50 at points spaced from the ends 16 of said dents. In accordance with the usual manufacture of such pitch band reeds each pitch band 14 comprises two wooden ribs 18 oppositely aligned adjacent opposite end portions of the dents hav- 55

ing flat inner sides 20 adjacent the opposite dent edges 22 at points equally spaced from the ends of said dents and arcuate, preferably semi-cylindrical outer sides 24 which may, if desired, be 5 provided with the longitudinal grooves 26 therein. Said longitudinal grooves 26 may be provided for the purpose of receiving therein reenforcing metal strips 28. A suitable cord means 10, preferably pre-impregnated with pitch 32, is spirally wound under tension around said ribs 18 to have each wind 34 thereof extend between all adjacent dents 12. As in the course of their manufacture the dents are somewhat compressed together and as the pitch is plastic, when the 15 dents 12 are assembled into the reed 10 an outer tubular covering or shell 36 of pitch exudes to the outer surface of the cord 32 to provide, when plasticized, a substantially homogeneous outer protective shell 36 of pitch extending throughout 20 the length of each pitch band and hence reed. The reed may be completed by the addition of the usual end members 38 having the caps 40 on each end thereof to receive the projecting ends of the wooden ribs 18. It is thus obvious that 25 the exterior pitch shell 36 may resiliently expand to permit any slight axial movement of one or more dents on an obstruction passing through the reed and resiliently contract to return the dents 12 to their desired original alignment and spacing.

As stated hitherto, considerable difficulty has been experienced in the prior art in having the edges 22 of one or more of said dents get out of alignment with those of the remainder of said 35 dents to thus continuously strike the shuttle and then tend to lessen its life, and the edges 22 of the dents 12 have tended to become permanently imbedded into the wooden ribs at unequal intervals due to the fact that a dent edge 22 may strike a softer spot in the wood than its next adjacent dent edge, and also break the resilient outer tubular pitch shell, thus destroying the rigidity imparted by it to the reed.

In accordance with the teachings of my invention, therefore, to prevent any of these contingencies taking place, I preferably provide means 42, in my preferred embodiment comprising flat protective strips of suitable hard material, such as metal, fibre, composition, etc. of substantially the width of the flat inner sides 20 of said wooden ribs 18 interposed between said flat inner sides 20 of said ribs 18 and said aligned dent edges 22 to clamp against the opposite edges 22 of said dents and thus keep the dents longi-

tudinally aligned throughout their length and to positively prevent the dent edges 22 from having an opportunity to become irregularly or otherwise individually imbedded into the wooden ribs 22. I have found in practice that pitch band reeds constructed in accordance with my invention are of greater initial strength, the life thereof is greatly prolonged, and the tendency to injure shuttles and shorten their life greatly reduced.

It is understood that my invention is not limited to the specific embodiment shown and that various deviations may be made therefrom without departing from the spirit and scope of the appended claims.

What I claim is:

1. In a pitch band reed construction, spaced dents, two aligned wooden ribs having flat inner sides opposite end portions of said dents at points spaced from the ends thereof and arcuate outer sides, pitch impregnated cord spirally wound around said ribs having winds thereof extending between the dents said pitch impregnated cord being compressed to join adjacent winds of said cord together to provide a substantially homogeneous and integral readily axially expandable and contractable shell for said ribs extending substantially throughout the length of said ribs, and means of substantially the width of the flat inner sides of said wooden ribs interposed between the flat inner sides of said wooden ribs and dents to maintain said dents in alignment and to prevent said dents from becoming imbedded into said wooden ribs.

2. In a pitch band reed construction, spaced dents, two aligned wooden ribs having flat inner sides opposite end portions of said dents at points spaced from the ends thereof and arcuate outer sides, pitch impregnated cord spirally wound around said ribs having winds thereof extending between the dents said pitch impregnated cord being compressed to join adjacent winds of said cord together to provide a substantially homogeneous and integral readily axially expandable and contractable shell for said ribs extending substantially throughout the length of said ribs, and flat protective strips of substantially the width of the flat inner sides of said wooden ribs interposed between the flat inner sides of said wooden ribs and dents to maintain said dents in alignment and to prevent said dents from being imbedded into said wooden ribs.

WALDO HENRY FISH.
